United States Patent Office

Des. 207,061
Patented Feb. 28, 1967

207,061

TOY AIRPLANE

Hugh L. Wallace, 275 Collier Road, NW.,
Atlanta, Ga. 30318

Filed Sept. 30, 1965, Ser. No. 87,226

Term of patent 14 years

(Cl. D34—15)

FIG.1

FIG.2

FIG. 1 is a perspective view showing the front and top of a toy airplane embodying the new design; and

FIG. 2 is a perspective view showing the front and bottom thereof.

I claim:

The ornamental design for a toy airplane, substantially as shown.
